UNITED STATES PATENT OFFICE.

JAMES C. LEDBETTER, OF BROOKLYN, NEW YORK, ASSIGNOR, BY MESNE ASSIGNMENTS, TO THE PROSPERITY COMPANY, INC., OF SYRACUSE, NEW YORK, A CORPORATION OF NEW YORK.

ELECTRIC GARMENT PRESS.

Application filed August 8, 1924. Serial No. 730,826.

This invention relates to pressing machines, and particularly to improvements in garment presses operated electrically both as to steam generating means for steaming the work, and press jaw heating means for heating the work.

An object of the invention is to produce a garment pressing machine having electrically heated press jaws as well as flash steam generating means whereby the same current employed to vaporize the water and produce steam is likewise employed to heat the pressing jaw surfaces.

A further object is to produce an electrically heated garment press and electrically heated high speed flash steam generating means, all of which is simple in construction rendering it possible to build pressing members or press jaws of very light weight construction as well as having comparatively few parts.

The accompanying drawings illustrate the principle and construction of a machine representative of the invention, but it will be understood by those conversant in the art how certain changes may be made without departing from the scope of the invention.

Figure 1 shows a sectional view through one of the pressing members looking down on top thereof showing a coiled electric resistance steam generating member, the said view being taken on the line 1-1 of Figure 2.

Figure 2 illustrates a longitudinal vertical sectional view made through the pressing jaw as along the line 2-2 of Figure 1.

Figure 3 illustrates a cross sectional view of the press jaw as made on the line 3-3 of Figure 2.

Figure 4 shows a fragmentary view of a pressing machine with the combined electric heating and steam generating means embodied thereon.

Figure 5 shows a detailed view of an electric connection established with the water feed end of a hollow wire electric current conductor and water transmitting member such as a German-silver tube; and Figure 6 shows a similar electric connection established with the innermost end of the said combination hollow wire current and water transmitting tube or wire. These two views are shown on an enlarged scale for illustration purposes. Furthermore, the hollow

wire current and water transmitting coil is shown enlarged throughout the drawings for the purpose of better illustrating the invention.

Pressing machines usually comprise a suitable frame 10 with means for opening and closing press jaws; and for example, a press lever 11 is oftentimes operated by toggle or link connections 12 which swing the press lever 11 on a frame fulcrum 13. The forward end of the press lever 11 carries a head 14 which rises and falls in relation to a buck 15. The work to be treated is inserted between the pressing jaw members 14 and 15 whereupon the work is heated, steamed and pressed by moving the head 14 downwardly against the buck.

For the purpose of illustrating the present invention, I have chosen the head 14 upon which a description is based outlining the embodiment of an entirely new combined steam generating means which consists in a hollow current and water transmitting wire 18 which is coiled within a steam spray chamber 19 formed in the head 14. The head 14 is equipped with a foraminous or perforated pressing face 20, the perforations 21 of which connect directly with the steam spray chamber 19. Preferably the steam spray chamber 19 is lined with an insulator sheet 22 by which the hollow German silver wire or tube 18 is positively separated and insulated from the pressing metal jaw 14. The perforated press plate or face 20 is usually equipped with a fabric press cloth 23 through which the steam discharges as it is ejected from the foraminous plate 20 onto the work supported on the buck 15.

The inner end of the hollow wire or coiled tubing 18 may be plugged up as indicated at 25 in Figure 6, and a lengthwise slot 26 is formed in the electrical resistance coil or wire 18, and the steam produced in the hollow wire is discharged from the slot 26 into the spray chamber 19, and the steam thereafter ejects with pronounced velocity outwardly through the foraminous plate 20 and press cloth 23 onto the work.

The other end 28 of the hollow wire 18 projects upwardly through the wall of the press jaw 14 where suitable connection is made with a water supply means as will be described. At each extremity of the hollow wire 18 there is located binding posts 29 and

30 by which a current feed wire 31 is connected in series with the said hollow wire 18 to feed current thereto. An electric cut-off switch 32 may be mounted on the press 5 at some convenient point by which the current may be turned on and off.

Current flows from the current supply transmission line 31 throughout the coil or coils of hollow wire 18 raising the temperature thereof which is transmitted through insulation 22 to the pressing face 20. At the same time water may be fed into the end 28 of the hollow wire which water is generated into steam by contact with the internal 10 wall of the hot wire, and by the time the water traverses the considerable length of tube, steam is discharged into the spray chamber 19.

It is to be understood that one or more 20 hollow water and current conductors 18 may be employed depending upon the amount of steam to be generated. The water and current conducting member is made of German silver or other electrical resisting material 25 thereby producing intense heat in the tube 18 when current flows therethrough.

Any suitable means may be employed for supplying water under pressure to the steam generating and electric transmission mem-

30 ber 18, and to this end a water tank 34 is mounted in fixed relation upon the press member 11 and swings about the fulcrum center 13 during the oscillating movement of the press lever 11 which avoids the necessity 35 of employing a flexible water joint between the water reservoir and flash steam generating head 14. The water tank is equipped with a pump 35 having a plunger 36 operated by a bell crank 37, and the bell crank 40 37 is manually operated at will by a push and pull rod 38 conveniently located towards the front of the machine and adapted to be reciprocated by the operator. A pipe 39 connects the pump 35 with the tank 34 45 whereby the water is drawn from the tank up into the pump 35 when the plunger 36 rises by spring pressure or other means. A discharge pipe 40 connects the pump with the outer end 28 of the hollow wire current 50 and water transmission tube 18. A valve box 41 containing a check valve governs the action of the pump 35 whereby the plunger 36 forces water from the pump 35 through the pipe 40 into the pressing head 14.

55 In the operation of the machine, the garment or other work is spread upon the buck 15, whereupon the operator closes the press head by foot power or other suitable means well known in the art. The garment is now 60 steamed by pulling the rod 38 which forces a small predetermined amount of water from the pump 35 through the hollow wire 18; and the water traverses such a considerable length of wire 18 as will effectively produce steam by the time the rapidly vaporiz-

ing water reaches the slot 36 whereupon the steam is ejected from the generating tube 18 outwardly into the spray chamber 19 rapidly filling this chamber which causes the steam to then flow with considerable pressure through the perforated press face onto the work thus steam moistening the garment, raising the nap, sterilizing it, and conditioning it for pressing and drying.

70 It will be noted that the electrically heated coil 18 is placed inside the foraminous spray chamber 19 and performs, among other things, three purposes, namely, it heats the press face 20, generates a predetermined amount of steam which is ejected 80 into the chamber about the coil, and serves to superheat the steam by reason of the fact that the steam flows in and around the external wall of the coil before it sprays outwardly through the perforations 21.

85 Water is periodically injected into the coil 18 to instantaneously generate steam at such times as steam may be required to condition the cloth, but it is to be understood that the heater coil 18 functions all the time to maintain appropriate temperature of the press jaw face so that dry pressing, using no steam, may be carried out.

90 What I claim is:

95 1. An electric pressing machine comprising in combination, cooperating pressing members, one of which is provided with a hollow steam spraying chamber and perforations leading therefrom through the pressing face of said member, a winding of electric current transmission wire disposed within said pressing member, said wire being hollow through which water is passed, electric current supply wires connected with the hollow wire, water force feed means connected to said hollow wire, and said hollow wire having a discharge opening which empties the steam therein generated into the aforesaid perforated steam spray chamber.

100 2. An electric pressing machine comprising in combination, cooperating pressing members, one of which is provided with a hollow steam spraying chamber and perforations leading therefrom through the pressing face of said member, a winding of electric current transmission hollow wire disposed within said perforated spraying chamber, one end of said hollow wire having a discharge opening by which steam is ejected 110 from the wire into the spray chamber, the other end of the hollow wire projecting through the pressing member, water feed forcing means connecting to the last-named hollow wire end, and current feed wires connected to both hollow wire ends.

115 3. An electric pressing machine comprising in combination, cooperating pressing jaws made with a hollow steam spray chamber having a foraminous pressing face, a coil of hollow water and electric current 120

125 130

- transmission wire placed inside the spray chamber by which the jaw pressing face is heated electrically and by which the wire is heated electrically, and means for forcing 5 water through the hollow heated wire to be vaporized into steam and discharged into said steam spray chamber.
4. A garment pressing machine comprising in combination, cooperating pressing 10 members provided with a chamber and perforated steam spraying face, a spiral electric heating coil installed in the chamber, said heating coil being hollow, electric feed wire connections established with the spiral 15 coil, and water feed means connected with the spiral coil.
5. A garment pressing machine comprising in combination, cooperating pressing members provided with a chamber and perforated steam spraying face, a spiral electric heating coil installed in the chamber, said heating coil being hollow, electric feed wire connections established with the spiral coil, said coil being provided at one end thereof 20 with an elongated steam spray discharge opening adapted to distribute and deliver steam to the perforated chamber, and water feed means connected with the coil.
6. An electrically heated and electrically 25 steam generating garment pressing machine,
- comprising in combination, a foraminous face pressing jaw, a coil of hollow resistance wire in the jaw, said coil having a steam discharge orifice at one end opening into and adjacent the foraminous pressing face, 30 water force feed means connected with the hollow wire, and electric current feed wires connected thereto.
7. A combination electric flash steam generator and electric heater for presses comprising, a press jaw provided with a steam chamber, a perforated press jaw face forming one wall of the chamber, a lining of insulation material covering the internal walls of the steam chamber and having perforations 35 in one wall leading through the face plate, an electrical resistance made of hollow wire placed in the chamber resting on the insulation, water force feed means connected with one end of the hollow wire, said wire 40 having a steam discharge opening therein formed at a distance from the water feed end, said steam discharge opening directly into the steam chamber thereby causing the steam to flow over the hot resistance wire 45 before it passes outwardly through the perforations.

In testimony whereof I affix my signature.

JAMES C. LEDBETTER.
